UNITED STATES PATENT OFFICE.

EDWARD ANTHONY SMALENBERGER, OF BROOKLYN, NEW YORK, ASSIGNOR TO
FRANKLIN L. DUEK, OF BROOKLYN, NEW YORK.

TELEPHONE SWITCH FOR RADIO SETS.

Application filed September 24, 1924. Serial No. 739,521.

To all whom it may concern:

Be it known that I, EDWARD ANTHONY SMALENBERGER, a citizen of the United States, residing at Brooklyn, in the county 5 of Kings and State of New York, have invented certain new and useful Improvements in Telephone Switches for Radio Sets, of which the following is a full, clear, and exact description.

10 This invention relates to switch devices for connecting a plurality of circuits in various relations to a common circuit. Such a switch device, for example, has considerable utility for the telephone circuits of 15 radio sets. In the customary operation of radio sets, the tuning is usually accomplished with head telephones, and after a desired station has been properly tuned in, connection is made to a loud speaking 20 receiver. In view of the difference in impedance between head sets and loud speakers, when the change is made from the telephones to the loud speaker, it is frequently necessary to effect a retuning in order to 25 obtain the desired clarity and volume from the loud speaker. It is frequently desirable to use the telephones simultaneously with the loud speaker and, while this may be satisfactory during a reception of relatively 30 weak signals, it is not practical when receiving relatively loud signals, such as the signals from local broadcasting stations. In various other circuit conditions, it is frequently desirable to connect auxiliary 35 circuits in various relations to a common circuit such as for balancing the same and selectively incapacitating either auxiliary circuit and it is to such circuits that this invention particularly relates.

40 An object of this invention is to provide an improved switching device which will satisfactorily solve the difficulties above mentioned and with which the auxiliary circuits may be connected in series with one 45 another and to a common circuit in such a manner that either auxiliary circuit may be incapacitated at will or shunted by a variable resistance.

50 An object of this invention is to provide an improved telephone switch for radio sets with which a change from the telephones to the loud speaker may be accomplished satisfactorily without retuning; with which the telephones and loud speaker may be used 55 simultaneously while receiving either weak

or strong signals without discomfort or annoyance to the operator; and with which either the telephones or loud speaker may be operated singly and selectively by simple manipulations.

60 A further object is to provide an improved switch for connecting either the telephones, or loud speaker, or both, to the radio receiving set selectively, which may be incorporated in a telephone plug.

65 A further object is to provide an improved switch for accomplishing each or all of the above objects which will be relatively simple, compact, durable and relatively inexpensive. Other objects and advantages will be apparent from the following description of an embodiment of the invention, and the novel features will be particularly pointed out in the appended claims.

70 The invention comprises various features 75 to which attention will be directed in connection with the following description of the application of the invention to telephone switches of radio sets.

75 In the accompanying drawing:—
80 Fig. 1 is an elevation of a switch constructed in accordance with the invention, with the closure wall removed;

85 Fig. 2 is a longitudinal sectional elevation of the switch;

85 Fig. 3 is a transverse sectional elevation of the same, with the section taken substantially along the line 3—3 of Fig. 1;

90 Fig. 4 is a transverse sectional elevation of a slightly modified construction, with the section taken along a line corresponding to that for Fig. 3; and

95 Fig. 5 is a diagrammatic illustration of the electrical connections, illustrating the use of the invention.

95 Referring especially to the particular embodiment of the invention which is illustrated in Figs. 1, 2, 3 and 5, a base member 1 of suitable insulating material, such as fibre, hard rubber or phenol condensation products, is provided with an aperture 2, extending from face to face, in which a spindle 3 is rotatably mounted. This spindle may conveniently comprise a screw, having a head 4, and an operating button 5 100 threaded upon the other end, the button 5 having a closed cavity into which the screw is threaded so that when the screw strikes the bottom of the cavity, the button will be 105 locked to the screw in such a manner that 110

when the button is manipulated, the screw will be rotated.

A closure wall or plate 6 is secured face to face against the base member 1 so as to cover the head 4 of the screw 3, and the wall 6 may have a cavity 7 upon its inner face providing clearance for the head of the screw. The face of the base member 1, which is covered by the wall 6, is provided with channels or grooves 8 and 9 along opposite sides and intersecting at one end, in which grooves resilient, conducting metal strips 10 and 11 may be disposed. A plug extension 12 is disposed at one end of the base member between said member and the wall 6, and this extension has the sleeve 13 and tip 14, as usual in telephone plugs, the strips 10 and 11 being connected at the end adjacent the plug extension to the sleeve 13 and tip 14 respectively so as to make electrical connections therewith at all times. The strips 10 and 11 also assist in anchoring the plug extension 12 to the base member.

The base member 1 and wall 6, at the end opposite the plug extension 12, may be provided with a plurality of spaced cooperating channels, each formed partially in both abutting faces of the member and wall, forming passages 15 through which the metal tips of the telephone cords may be inserted when establishing electrical connections between them and the interior of the switch. The strips 10 and 11, at the end adjacent the passages 15, terminate in spring contacts 16 and 17 respectively, in approximate alignment with the two outer passages 15, so that when the metal tips of telephone cords are inserted in the two outer passages, they will make electrical contact with the contacts 16 and 17 and be frictionally held within the passages thereby.

A metal strip 18 is disposed edgewise in a groove in the base member 1, and at its end adjacent the passages 15 carries a double U-shaped contact element 19, with the strip extending between and secured to two adjacent arms of the double U-shaped member. The free arms 20 of the double U-shaped member are disposed in approximate alignment with the two inner passages 15, so that when the metal tips of telephone cords are inserted in these two inner passages, they will make electrical contact with the free arms of the double U-shaped contact element 19 and be frictionally held in the passages 15 thereby.

The other end of the strip 18 is twisted through approximately 90 degrees to form a leaf spring end portion 21, and the extreme end of this end portion 21 is provided with a slot 22 which embraces the spindle 3 and bears upon the shoulder between the head 4 and the shank of said spindle. This spring end 21 is preferably normally flexed, so that it constantly urges the spindle 3 in

a direction to hold the button 5 against the outer face of the base member, thus creating sufficient friction to hold the button in various angular positions, into which it may be adjusted. A pointer or indicator 23 may be secured to the button 5, for rotation therewith in any suitable manner, such as by a pin 24. The pointer 23 will thus indicate upon a suitable scale (not shown) provided upon the outer face of the base member 1, the various angular adjusted positions of the button 5.

An arcuate channel or groove 25 is provided upon the inner face of the base member 1, connecting the channels or grooves 8 and 9. In this channel an arcuate element 26 may be disposed, which element extends substantially the whole length of the groove 25. The strips 10 and 11 are provided with ears 27 and 28 respectively, which extend toward one another and overlie the ends of the element 26 and confine it within the groove 25, as shown particularly in Figs. 1 and 3. The element 26 is formed preferably of insulating material, and adjacent one end, such as the end adjoining the ear 27, is provided on its outer face with a notch or cut away portion 29 for a purpose to appear presently. The outer surface or face of the element 26 between the notch 29 and the other ear, such as 28, is provided with a conducting coating or surface 30 having a high resistance, this surface or coating extending beneath the ear 28 so that it will always be electrically connected to the spring strip 11. This conducting surface of high resistance does not extend across the notch 29 for reasons which will appear presently.

A contact arm 31 is coupled to the head 4 of the spindle 3 in any suitable manner so as to rotate with the spindle. This contact arm is preferably a resilient spring member, which at its outer or free end bears resiliently upon the arcuate element 26. By an angular rotation of the spindle 3, the contact arm 31 may be placed over and in contact with either ear 27 or 28, or in any position upon the conducting high resistance coating or surface 30, which is in electrical connection with the ear 28. When this contact arm is over the notch 29, it will not be in electrical contact with either of the ears 27 or 28 and not in contact with the conducting surface 30. With this construction, it will be observed that the double U-shaped contact element 19, which is connected to the contact arm, may, by a rotation of the button 5, be electrically connected selectively to either of the contact ears 27 and 28, or to any point of the resistance surface 30, or to none of them when the contact arm 31 is placed over the notch 29.

Referring particularly to Fig. 5, let it be assumed that the metal tips 32 and 33 of

the telephone cords 34 and 35, leading to a head set 36, are inserted in two adjacent passages 15, one of which leads to the contact strip 11, in which position, the telephone cord tips will be in electrical contact with the spring strip 11 and the contact element 19. Let it be assumed that the metal tips 37 and 38 of telephone cords 39 and 40 leading from a loud speaker 41, are inserted in the other two passages 15, so as to be in electrical contact with the spring strip 11 and the contact strip 19. With the parts connected in this manner, when the button 5 is rotated to carry the contact arm 31 into a position over the notch 29, the head set 36 and the loud speaker 41 will be connected in series with one another and to the sleeve 13 and tip 14.

When the plug extension 12 is placed in a jack, the sleeve 13 and tip 14 thereof will be electrically connected to the telephone circuit of a radio set, and since the strips 10 and 11 are connected to the sleeve and tip they also will be connected to the telephone circuit of the set. One terminal of the head set will be connected to the strip 11 and a terminal of the loud speaker will be connected to the other strip 10. The other terminals of the head set and the loud speaker will be connected together through the spring contact element 19, and together will be connected to the strip 18 and the contact arm 31. When the contact arm 31 is over the notch 29, the head set and loud speaker will be connected directly in series with one another and in series with the telephone circuit from the radio set.

When the button 5 is rotated to carry the contact arm into engagement with the ear 28 for example, the head set 36 will be short circuited by the contact arm 31 and will therefore be ineffective, so that all of the current from the telephone circuit in the radio set will pass directly through the loud speaker. When the button 5 is rotated to carry the contact arm 31 into contact with the ear 27 on the other strip, the loud speaker will be short circuited and the telephones will be connected directly across the telephone circuit from the radio set. Thus by rotating the button 5 into contact with either of the ears 27 and 28, either the telephones or the head set will be rendered effective and the other ineffective.

When the button 5 is rotated to carry the contact arm 31 over the conducting surface 30 of high resistance, the head set will not be directly short circuited but will be shunted by the resistance of the coating or surface 30 between the ear 28 and the contact arm 31. This resistance will vary, of course, as the contact arm moves across the conducting surface 30. Thus by rotating the button 5, the resistance shunted across the head set may be varied, and by

reason of this shunt more or less of the current from the telephone circuit of the radio set will be diverted directly to the loud speaker instead of passing through the head set.

In order that the variation in resistance of the surface 30 may be as rapid as possible, the element 26 and surface 30 may be tapered as shown in Fig. 1, or the character of the conducting surface may be varied so that its resistance will change progressively along its length. For example, the surface of the element 26 may be impregnated with graphite or any other conducting material, so as to provide a conducting surface of high resistance, and by varying the degree of impregnation along the element, the rapidity of change in resistance may be varied. This feature may also be used in connection with the tapering of the surface if a still varied degree of change in resistance is desired.

In Fig. 4 I have illustrated a modified construction of the element 26, the modified element comprising two sections 42 and 43, the section 43 being of insulating material. The section 42, which is a conducting section, tapers from the end connected to the ear 28 to the notch 29 and is secured upon the oppositely tapered part of the insulating section 43. This modified element 26 is secured in the groove 25 as in the preceding embodiment and, as the contact arm moves over the section 42, the resistance will vary progressively according to the distance of the contact arm from the ear 28 and also by reason of the rapidity of change in resistance due to the tapering of the conducting section.

In both embodiments of the invention, the element 26 is confined in the groove 25 by reason of the overlying ears 27 and 28 of the strips 10 and 11, and the strips 10, 11, and 18 are held in their grooves by the wall 6. The wall 6 is secured to the base member 1 in any suitable manner such as by screws 44 which pass between them. The spring end 21 of the strip 18 creates sufficient friction upon the spindle 3 to hold it in various adjusted positions and the friction of the contact arm 31 when in contact with the conducting surface or with the ears, also assists in holding the button in adjusted positions.

When operating this device during the reception of relatively strong signals, such as from local stations, the station may be tuned in by the head set, and in order that the sounds emitted from the head set will not be too great therefor or too great to be comfortable to the ears of the operator, the button 5 may be turned to carry the contact arm 31 over the conducting surface 30 and vary the current which will be shunted across the head set. In this manner the volume of

sound in the head set may be varied until it is comfortable, without interfering with the operation of the loud speaker. The resistance and impedance in different head sets 5 and loud speakers vary with the particular design of instrument which may be used at any time, and consequently it is desirable that this resistance be variable, as provided by this invention, so that a proper balancing 10 of resistances and impedances at any time and with any instruments may be secured in a simple manner. When relatively weak signals are being received, the contact arm 15 may be shifted to increase the proportion of current passing through the head set, so that the latter will produce the signals with the desired volume. If at any time it is desired to cut out either the head set or the 20 loud speaker, it may be done by rotation of the contact arm into engagement with the ears 28 or 27 respectively.

If it is desired to operate both head set and loud speaker in series with one another, it is merely necessary to shift the contact arm 25 31 into the notch 29, in which position it will not have electrical contact with either strip 10 and 11 and the head set and loud speaker will be directly in series with one another. If the conducting surface 30 be- 30 comes worn, broken or deteriorates, a new element 26 with a new conducting surface or coating may be readily inserted in the groove 25, since all the parts are held in their grooves by the wall 6. The ends of 35 the notch 29 are preferably beveled so that the contact arm will readily ride up either end of the same as it is being shifted in either direction.

While the invention has been described in 40 connection with a plug for connecting various types of telephone receivers to a telephone circuit, it will be understood that this is illustrative only and that the invention has many applications to other electrical arts. 45 It will also be obvious that various changes in the details and arrangements of parts, which have been herein described and illustrated, for the purpose of explaining the nature of the invention, may be made by 50 those skilled in the art within the principle and scope of the invention as expressed in the appended claims.

I claim:

1. A telephone switch for radio sets, comprising a pair of conductors for connection in the telephone circuit of a set, a support for the conductors, a switch member carried by the support for movement in a definite path thereon, spaced contact elements, one connected to each of the two conductors and another to the switch member, whereby a telephone receiver may be electrically connected between one of the conductors and the element that is connected to the switch member, and another receiver between the other of the

said conductors and the switch member, and switch elements connected to the two conductors and disposed in spaced relation to one another within the path of the switch member, whereby either receiver may be temporarily short circuited by moving the switch member into engagement with that switch element which is connected to the same conductor that that receiver is directly connected to, and both receivers rendered active 75 and placed in series by moving the switch member out of engagement with both switch elements. 70

2. A telephone switch for radio sets, comprising a pair of conductors for connection in the telephone circuit of a set, a support for the conductors, a switch member carried by the support for movement in a definite path thereon, spaced contact elements, one connected to each of the two conductors and another to the switch member, whereby a telephone receiver may be electrically connected between one of the conductors and the element that is connected to the switch member, and another receiver between the other of the said conductors and the switch member, switch elements connected to the two conductors and disposed in spaced relation to one another within the path of the switch member, whereby either receiver may be temporarily short circuited by moving the switch member into engagement with that switch element which is connected to the same conductor that that receiver is directly connected to, and both receivers rendered active 90 and placed in series by moving the switch member out of engagement with both switch elements, 85 and a resistance element within the path of the switch member, whereby either receiver may be temporarily short circuited by moving the switch member into engagement with that switch element which is connected to the same conductor that that receiver is directly connected to, and both receivers rendered active 95 and placed in series by moving the switch member out of engagement with both switch elements, and a resistance element 100 within the path of the switch member and electrically connected to one of the switch elements whereby as the switch member moves over the resistance element a variable resistance will be connected across one of the receivers while they are in series whereby the relative currents through said 105 receivers may be balanced or given various desired relative values. 110

3. The telephone switch for radio sets, substantially as set forth in claim 2, in which the resistance of the resistance element varies throughout its length. 115

4. The telephone switch for radio sets, substantially as set forth in claim 1 in which the support carries a jack plug to the tip and sleeve of which the conductors are 120 connected respectively. 120

5. The telephone switch for radio sets, substantially as set forth in claim 1 in which the spaced contact elements have clips for detachably clamping the usual telephone cord tips of receivers. 125

6. The telephone switch for radio sets, substantially as set forth in claim 1 in which the support carries a jack plug to the tip and sleeve of which the conductors are 130

- connected respectively, and the spaced contact elements have clips for detachably clamping the usual telephone cord tips of receivers.
7. A switch for connecting a plurality of auxiliary circuits to a common circuit in various relations comprising a pair of spaced contacts to which the conductors of said common circuit are connected, said auxiliary circuits being connected in series and to said contacts, means including a contact arm connected to the series connection between the auxiliary circuits and movable selectively into engagement with either of the spaced contacts for selectively shunting either of the auxiliary circuits.
8. A switch for connecting a plurality of auxiliary circuits to a common circuit in various relations comprising a pair of spaced contacts to which the conductors of said common circuit are connected, said auxiliary circuits being connected in series and to said contacts, means including a contact arm connected to the series connection between the auxiliary circuits and movable selectively into engagement with either of the spaced contacts for selectively shunting either of the auxiliary circuits, and a resistance element disposed in the path of the contact arm and connected to one of said spaced contacts so that the resistance of the shunt across one of the auxiliary circuits may be selectively varied.
9. A switch for connecting a plurality of auxiliary circuits to a common circuit in various relations comprising a pair of spaced contacts to which the conductors of said common circuit are connected, said auxiliary circuits being connected in series and to said contacts, means including a contact arm connected to the series connection be-
- tween the auxiliary circuits and movable selectively into engagement with either of the spaced contacts for selectively shunting either of the auxiliary circuits, and means including a contact arm connected to the series connection between the auxiliary circuits and movable in a path in which it will engage said spaced contacts successively so as to shunt either of the auxiliary circuits, and a resistance element disposed between said spaced contacts within the path of said arm and electrically connected to one of said spaced contacts whereby the resistance of the shunt across one of said auxiliary circuits may be varied to a considerable extent, the resistance element terminating some distance from the other contact so that when the contact arm is between the resistance element and said other contact, the auxiliary circuits will be connected in series.
10. A switch for connecting a plurality of auxiliary circuits to a common circuit in various relations comprising a pair of spaced contacts to which the conductors of said common circuit are connected, the auxiliary circuits being connected in series with one another and to said contacts and a non-inductive variable resistance device interposed between one of said contacts and the series connection between the auxiliary circuits whereby one of said auxiliary circuits may be shunted by a variable non-inductive resistance, said resistance device being movable into a condition in which the shunt is ineffective and also into a condition which directly shunts the other of said auxiliary circuits.

In witness whereof, I hereunto subscribe my signature.

EDWARD ANTHONY SMALENBERGER.
